VARIABLY TUNED PIEZO-ELECTRIC
RESONATOR

Mendel Osmos, Berlin, Germany, assignor to Tele-funken Gesellschaft fur Drahtlose Telegraphie m. b. H., Berlin, Germany, a corporation of Germany

Application May 4, 1929, Serial No. 360,395
In Germany June 23, 1928

7 Claims. (Cl. 250—36)

It is known in the prior art that the wave-length of a circuit controlled by a crystal may be slightly altered by variation of a capacity connected in series with the crystal.

5 However, this method allows of insuring only very small changes in the wave-length (see, for instance, Jahrbuch der drahtlosen Telegraphie and Telephonie, vol. 29, Heft 1, p. 23). Indeed, as demonstrated in the article before 10 cited, the relative alteration in wave-length thus insurable amounts to only one-tenthousandth.

Even by changing the inter-electrode distance of the crystal—a method less suitable for other reasons—the relative alteration in the wave 15 2.5 was only $\frac{1}{10000}$. As has been shown by further tests this method was attended with a rather marked decrease in the useful current when the wave-length was reduced.

20 It is therefore an object of the present invention to provide a crystal controlled circuit which permits certain variations in wave-length using crystals each of which has a predetermined natural period.

25 Now, according to the present invention a considerably greater change in the wave-length is attainable if, say, two crystals are connected instead of only one according to former practice, and if one or the other crystal is cut in circuit 30 alternately and then the two crystals are connected in parallel.

The manner in which the present invention is carried out will be more clearly understood from the following description taken in connection with 35 the accompanying drawing, in which:

Fig. 1 shows one arrangement for varying the wave-length of a crystal controlled circuit;

Fig. 2 shows an arrangement in which various wave-lengths may be had with one or two 40 crystals in the circuit; and

Fig. 3 shows a modification.

In Figure 1 is shown an oscillation generator in which the frequency of the oscillations generated is determined by a circuit including a 45 crystal K in series with a tuning capacity C_k. The wave length generated in the thermionic tube to a great extent is determined by the nature of the crystal K. This frequency, however, may be varied over limited range by means of the tuning capacity C_k.

In Figure 2 two crystals, K and K₁, are arranged to be connected alternately or simultaneously in circuit by means of switches a and a₁ with tuning capacities C_k as shown. Furthermore, these crystals K and K₁, and/or their

tuning capacities, may be connected in series with each other and in the resonance circuit with switching means not shown.

Experience has shown that even when both crystals have the same, or nearly the same, natural period, the addition of the second crystal insures a considerable variation in wave-length. When the two crystals are connected in parallel a new frequency, differing from the individual crystal frequencies, is produced. This new frequency is not the algebraic sum of the individual crystal frequencies. When the two crystals are connected in parallel each tends to resonate at its particular frequency, but each pulls the other away from its normal frequency so that a new distinct frequency is produced by the two crystals, which appear to be entrained. This new frequency can be varied over a predetermined frequency range by the capacities.

If the circuit of one or both crystals k k₁ is untuned in relation to the natural period of the latter, for instance, by the aid of variable capacities C_k (see Fig. 2), then, as shown by practical experiments a relative frequency 25 change of about 5/10000 or even slightly more is obtainable by the opening and closing of switch a.

Another advantage is that the useful current decreases far less when a frequency change 30 is insured by means of two crystals as shown in Fig. 2 than when only one crystal is employed as in Fig. 1.

The crystals could also be connected in series 35 relation to each other, and then again a different wave-length is obtained.

The method here disclosed offers a still further advantage; for instance, if a transmitter is required to send out various waves, a separate crystal has heretofore been required 40 for each wave, so that for "n" waves, "n" crystals were needed. According to this invention, however, even with only two crystals differing slightly in their natural period, at least four waves can be used at will, to wit:

1. When the crystal K only is connected into the frequency determining circuit, including the tuning capacity C_k, the frequency of the oscillations generated will be determined by K and C_k.

2. When the crystal K₁ only is connected into the frequency determining circuit, including the tuning capacity C_k, a different frequency, assuming the values of K and K₁ are different, will be generated.

45

50

55

3. Now, if both crystals are connected in parallel, obviously the electrical characteristics of the frequency determining circuit will be different than when either crystal is connected separately, and a third frequency will be generated by the generator.

4. If both crystals K and K_1 are connected in series, as described above, by switching means (not shown), again it will be obvious to anyone familiar with the radio art that the natural frequency of the frequency determined circuit will be different than in any of the prior cases.

If three crystals are provided in lieu of two, then 17 different wave-lengths are obtainable as can be seen from a simple calculation, even without the use of capacities C_k .

The number of wave-lengths obtainable grows very rapidly with the number of the crystals since a great number of group arrangements or combinations of the crystals are feasible, quite apart from series and parallel connection. For instance, with four crystals 100 waves are obtained.

25 But if the crystal circuits are detuned in relation to one another by different capacities (as indicated, for instance, in Fig. 2 by capacities C_k), the number of ensuing frequencies can be considerably increased. The inter-electrode 30 capacity of the tube may be partially neutralized by the condenser C_n connected as shown.

35 Series connection of the crystals offers the particular advantage that the tuning of the circuit turns out to be much sharper, a fact which is especially valuable in receiver tubes.

One exemplification for radio frequency reception is shown in Fig. 3. Between antenna A and the grid circuit of a radio frequency amplifier b there is inserted an intermediate 40 circuit tuned by crystals k . In broadcast reception, whenever the local station disturbs long-distance reception, the influence of the local station can be very effectively eliminated by means of suitable choice of the crystals.

45 For each long-distance station a distinct crystal combination is used; for example, for the Cologne broadcast station a certain crystal or crystal combination, for the Paris wave another crystal or crystal combination, etc. That a great number of frequencies can be obtained with this arrangement may be seen from the following: Assume that the crystals K of Figure 3 are all of individual characteristic and, further, that the crystals K of Figure 3 are numbered from 1 to 6 in sequence from the top 50 of the page to the bottom. Crystals 1, 2 and 3 will be in the upper group and crystals 4, 5 and 6 will be in the lower group. Merely by manipulating the switches shown combinations

60 of the crystals as follows may be placed in series with the tuning condenser C in the coupling circuit 1, 4; 1, 5; 1, 6; 2, 4; 2, 5; 2, 6; 3, 4; 3, 5; 3, 6; 1, 2, 4; 1, 2, 5; 1, 2, 6; 1, 2, 3, 4; 1, 2, 3, 5; 1, 2, 3, 6; 1, 4, 5; 2, 4, 5; 3, 4, 5; etc. Each combination will cause the circuit to be normally resonant at a different frequency. This is so obvious that it is thought needless to go any further into the reasons why this is so.

70 The natural frequencies of the crystals need not be of any definite relative values. All that is imperative is that the circuit including the crystal combinations or groups, with the aid of the tuning means, resonate at the desired 75 frequency.

Having thus described the invention, I claim:

1. A radio frequency oscillator adapted to be variably tuned from one value of wave-length to another, in combination with a piezo-electric control device having a plurality of piezo-electric crystal elements, and switching means selectively to connect said elements in different combinations, said device being adapted to control said oscillator to hold substantially constant the frequency of oscillations produced at various wave-lengths of said oscillations, the number of crystal elements in the device being less than the number of wave-lengths to which the oscillator may be set for operation under control of the device and the control frequency of said combination of control devices being greater than any beat note capable of being produced by the difference frequencies from said piezo-electric elements. 5

10 2. In combination an oscillation generator, a plurality of piezo-electric control devices connected thereto, each of said devices having a natural frequency of vibration, and switching means selectively to disconnect any one or more of said devices, leaving at least two of said devices connected to said generator, and circuit controlling means for controlling the frequency of oscillations produced by said generator at a value substantially constant and different from the natural frequency of any one of said connected crystals by an amount less than the beat 15 frequencies between said connected crystals. 20

25 3. In combination an oscillation generator, a plurality of piezo-electric control devices connected thereto, each of said devices having a natural frequency of vibration, a variable impedance connected to each of said devices, and means selectively to disconnect any one or more of said devices, leaving at least two of said devices connected to said generator, said variable impedance means being adapted to control the frequency of oscillations produced by said generator at a value substantially constant and different from the natural frequency of any one of said connected crystals and from the algebraic 30 sum of the natural frequencies of the connected crystals. 35

4. In combination, a tunable circuit, a plurality of mechanical vibrating devices having different natural periods of vibration, and switching mechanisms for combining said devices to produce oscillations of a frequency differing from that represented by the sum or difference of the individual natural periods of vibration of said devices. 50 55

5. In combination, a tunable circuit, two piezo-electric crystal resonators associated with said circuit, each of said crystal resonators having a natural period of vibration, switching devices for combining said two piezo-electric resonators to produce oscillations of a frequency which differs from the natural period of vibration of any one of said two resonators and from the algebraic sum of the natural periods of said resonators, and variable frequency controlling 60 means for varying the frequency of the said oscillations over a predetermined desired frequency range. 65

6. In combination, a tunable circuit, a plurality of piezo-electric crystal resonators having different natural periods of vibration, manually operable switching devices for connecting groups of said crystal resonators in said circuit to produce oscillations of a frequency which differs from the natural period of any 70 75

one of said resonators, and capacitive elements for controlling the frequency of said oscillations to obtain a predetermined frequency which differs from that represented by the sum or difference of the individual natural period of said resonators.

7. In combination, a tunable circuit, a plurality of piezo-electric crystal resonators associated with said circuit, each of said resonators taken alone having a natural period of vibration, switching means to selectively connect

any one of said resonators or combinations of one or more of said resonators to said circuit for producing a period of vibration different from the natural period of any one of said resonators included in the combination, said piezo-electric crystal resonators being adapted to control said tunable circuit at a frequency which differs from that represented by the sum or difference of the individual natural periods of said resonators.
